J. J. BAEHR

GARMENT PROTECTOR

Filed July 10, 1922

INVENTOR,
John J. Baehr,
BY
James J. Huestis &
ATTORNEYS.

UNITED STATES PATENT OFFICE.

JOHN J. BAEHR, OF NEW ORLEANS, LOUISIANA.

GARMENT PROTECTOR.

Application filed July 10, 1922. Serial No. 573,878.

To all whom it may concern:

Be it known that I, JOHN J. BAEHR, a citizen of the United States, residing at New Orleans, in the parish of Orleans and State 5 of Louisiana, have invented new and useful Improvements in Garment Protectors, of which the following is a specification.

My present invention pertains to apparel, and it contemplates the provision of a device 10 through the medium of which the shirt and coat of the person wearing the device will be prevented from becoming soiled or mussed.

The invention further contemplates the 15 provision of a device that is simple and convenient to adjust and wear and when properly positioned on a person a free circulation of air will take place at all times between the shirt or coat and back of the wearer of 20 the garment.

The invention is further adaptable for use of persons compelled to remain in a seat for a length of time, for instance those travelling in a motor vehicle, train or the like, and 25 when employed liability of perspiration from soiling the garment exposed to the back of the vehicle will be precluded.

Other objects and characteristic features 30 of the invention will be fully understood from the following description and claim, when the same are read in connection with the specification and drawings, accompanying, in which:

Figure 1 is a top plan view of my novel 35 garment.

Figure 2 is a transverse sectional view thereof.

In both views of the drawings similar numerals are employed to designate corresponding parts.

My novel device is preferably formed of cork and other suitable light nonmoisture absorbing material, and is also preferably constructed in the shape illustrated. The 45 said device comprises the discs 1, that may be round as shown or any other shape compatible with its purpose, the said discs 1 are secured by thread or cords 2, that pass entirely through each of the discs 1, and there- 50 by secure said discs to each other. It will be noted that the discs are secured to each other with a slight intervening space there- between and this provision is made in order to take care of contraction and expansion of 55 the discs due to moisture.

The device formed in the manner illus-

trated of the discs 1 are provided with the tapes 4 having at their upper ends the loops 3, and hence it will be seen that the device may be placed over the shoulders and will 60 be properly retained against the back. The loops serve to receive the arms of the wearer and the device as a whole may either be worn under the shirt or coat with equal facility and comfort, and because of the light construction of the protector the finished appearance of a shirt or coat will not be detracted from.

It will be manifest that besides acting in its primary capacity, the device is also 70 adapted to act as a support and soft rest for the back.

It will be manifest that because of the non-absorbing material of the device perspiration cannot settle on the back of the 75 wearer and the construction furthermore relieves stains from matter in the material of which the device is made. The discs may be made of any suitable material compatible with their purpose and when desired may be 80 treated with a coat of enamel. The protector, moreover may be made of any shape to conform to the different formations of individuals.

Manifestly a catch may be employed to 85 secure the protector to the trousers of the wearer if desired and the device is also adapted for use by a woman and if she does not care to don the garment the same may be attached to the back of the chair in which 90 she is seated.

Having described my invention, what I 95 claim and desire to secure by Letters-Patent, is:

In a device for the purpose set forth, the combination of a series of cork discs secured adjacent each other, in substantially a horizontal plane to produce a garment slightly wider at its upper end than at its lower end, tapes secured to discs running from the upper corners substantially diagonally of said garment, and having loops at their upper end whereby the device may be adjusted to the back of the wearer.

In testimony whereof I have hereunto set 105 my hand in presence of two subscribing witnesses.

JOHN J. BAEHR.
